Primary Examiner — Marianne Pandozzi(74) *Attorney, Agent, or Firm* — Kilpatrick Townsend & Stockton LLP(57) **CLAIM**

The ornamental design for a beverage dispensing tower, as shown and described.

DESCRIPTION

FIG. 1 is a perspective view of a first embodiment of a beverage dispensing tower, showing our new design;
 FIG. 2 is a rear perspective view thereof;
 FIG. 3 is a front view thereof;
 FIG. 4 is a rear view thereof;
 FIG. 5 is a right side view thereof;
 FIG. 6 is a top view thereof;
 FIG. 7 is a perspective view thereof showing an environment; and,
 FIG. 8 is a perspective view thereof showing an environment.

The left side views of the embodiments of the beverage dispensing tower are mirror images of the right side views thereof illustrated in FIG. 5.

The broken lines in the drawing depict environmental subject matter only and form no part of the claimed design.
